UNITED STATES PATENT OFFICE.

JAMES R. WYATT, OF PHILADELPHIA, PENNSYLVANIA, ASSIGNOR TO THE AJAX METAL COMPANY, OF PHILADELPHIA, PENNSYLVANIA, A CORPORATION OF PENNSYLVANIA.

FORM FOR OUTLINING ELECTRIC-FURNACE CHANNELS.

1,313,571.

Specification of Letters Patent.

Patented Aug. 19, 1919.

Application filed January 10, 1918. Serial No. 211,124.

To all whom it may concern:

Be it known that I, JAMES R. WYATT, a citizen of the United States, residing at 2024 S. 21st street, Philadelphia, in the 5 county of Philadelphia and State of Pennsylvania, have invented a certain new and useful Form for Outlining Electric-Furnace Channels, of which the following is a specification.

10 My invention relates to a form for outlining the resistor channel in an electric furnace. The purpose of my invention is to protect against injury to the lining by expansion of the form. I also provide for 15 sintering the adjoining lining material.

A further purpose is to provide a composite form made up of different materials.

20 A further purpose is to provide a space extending longitudinally of the form and either empty or filled with a readily removable substance facilitating the destruction of the form.

25 A further purpose is to provide a metallic secondary path, used in starting the furnace, and at the same time relieve against undue expansion by interposing a compressible or removable portion to prevent breakage of the refractory lining.

30 A further purpose is to give room for expansion of a metallic secondary form, taking care of either longitudinal or transverse expansion or both.

35 A further purpose is to relatively weaken the top of a metallic secondary form so as to make that its weakest section.

A further purpose is to practise the process herein set forth.

Further purposes will appear in the specification and in the claims.

40 I have preferred to illustrate my invention by forms which have been tested by me and which will illustrate the principles of my invention.

Figure 1 is a side elevation of a type of 45 furnace illustrated in my Patent No. 1,201,671 with a metallic secondary form in place.

Fig. 2 is a side elevation of such a form

as is shown in Fig. 1 with fillers providing room for expansion.

50 Figs. 3 and 4 are a section upon line 3—3 and a top plan view, respectively, of Fig. 2.

Figs. 5, 6, 7, 8 and 9 are cross sections of variant forms taken at any point in the lower part of the resistor and perpendicular 55 to it; for example, at section line 5—5 of Fig. 2.

In the drawings similar numerals indicate like parts.

60 In electric furnaces of the general character indicated in Fig. 1, some "form" is needed for outlining the channel or "path" for the molten secondary path. After the lining is rammed about this form it is necessary to provide some means of removing 65 the form.

70 While the full advantage of my invention requires a metallic circuit throughout the channel length to act as a secondary in drying out and sintering the lining, that portion of my invention which relates to facilitating the removal of the form was first practised by me by the use of a wooden form having a hole throughout its length so that a flame could be driven through, about the 75 angle. It is very desirable to use compressed air and oxygen to maintain the "spark."

75 This wood form presents the advantage as compared with solid metal (unrelieved 80 for expansion) that the wood does not injure the lining by expansion whereas the metal stretches and fractures it. It has the disadvantage that being a non-conductor of electricity, the wooden form cannot be used as 85 a secondary to dry out and sinter the adjoining lining.

I have obtained part of the advantage of each of these by using a composite form of 90 which one part is metal and the other is removable or compressible to provide for expansion. It is quite desirable to use a composite section throughout, relieving against both transverse and longitudinal expansion, but even where the cross section 95 of the major channel length is solid metal,

the injurious effects of the lengthwise expansion of the form may be relieved by a composite section throughout a part of the channel length. Whichever of these parts of 5 my invention be used—and I prefer to use both—the form, preferably with the addition of some molten metal, can be used as a secondary for the purpose of sintering the surrounding lining material and starting 10 the furnace in operation.

In showing my invention in connection with the furnace of my Patent No. 1,201,671 it is my intention to use this type as typical of those furnaces where room for expansion 15 of the metallic form must be allowed in order to prevent breakage of the adjoining refractory; and I recognize that it is applicable to various other forms of furnaces also.

20 In the illustration an outer furnace jacket is shown at 5 connecting with a channel casing 6 by an intervening transformer 7. The latter is provided at the top and bottom with channel members 8 and 9. The parts 25 are connected by bolts 10 passing through ears 11, 12 upon the jacket and shell respectively. The top of the furnace is formed by a separate shell 13 united to the jacket 5 by ears 14 and bolts 15. The top 30 opening is closed by a plug 16. The transformer winding is shown at 17. For further desired detail as to the preferred construction of the furnace itself, reference is made to my patent above indicated.

35 In furnaces of this general character a lining or "refractory" 18 is used, which may be of any suitable material which will withstand the heat and which is a poor conductor or a non-conductor of electricity.

40 I have successfully used an asbestos paste which is rammed to position about the channel form, preferably by a power hammer. The interior shape of the furnace pool may be outlined either by another form or 45 by a tool used with the hammer.

Taking up first the relief against longitudinal expansion of the channel form:—With a shape of channel such as shown in Fig. 1 a full metal form could not be heated 50 to any considerable extent without expanding considerably in the direction of the lengths of the straight channel parts, with resultant breakage of the refractory. I have discovered that the great advantage 55 of the metal form in permitting drying and sintering of the lining and in supplying a complete metallic starting secondary may be secured without breakage from longitudinal expansion by filling out the outer parts

60 of the frame in the direction of the expansion with temporary "fillers" which will not interfere with the expansion of the metal into the space originally occupied by the fillers. These fillers in connection with the 65 metal initially fill the full cross section of

the channel while the lining is being packed about them.

The fillers illustrated can be removed before the form is heated, giving the room previously occupied by the fillers for expansion. 70

Though my form as illustrated might appropriately be called a stirrup and is described in connection with a furnace intended primarily for melting brass or similar alloys it is obvious that the contour and 75 section will vary with the shape of the furnace and that the form is suitable also for the use in furnaces handling other materials. For the brass furnace I have found it quite desirable to use a stirrup of brass because 80 it combines the proper electrical resistance and melting point. For convenience, therefore, and in explanation, but not in limitation, I shall describe this part of my invention as it has been applied to the brass 85 furnace shown.

In applying the stirrup (whether of solid or composite cross section at other points, as hereinafter discussed) within the furnace casing the form is first desirably waxed in 90 order to fill up any interstices or irregularities to which the refractory material might adhere and to provide the space occupied by the wax as expansion room when the form is heated. I prefer to make this coating thin and for one type of furnace found a coating of a sixty-fourth of an inch thickness very satisfactory.

The form is held in position by any suitable means, not shown while the lining material is filled in about it and tamped to position. The inner limit may be the transformer winding or a shell 17' thereabout. The placing of the lining within the body 95 of the furnace need not be here described.

For a furnace having V shaped channel as indicated in Fig. 1 the sides 19, 20, of the form, corresponding to the major portion of the channel, are flat and longitudinal expansion will take place in a straight line, 100 making the total form width between the sides 21, 21', wider because of the expansion. For the purpose of allowing room for this expansion I provide fillers 22, 22 which do not show in Fig. 1, having been 105 removed. They have combined thickness at least equal to the amount of expansion in the width of the form, totaling with the addition of the form at each side the thickness of the side portion of the channel. I 110 have obtained excellent results using temporary removable or easily destructible fillers of wood and removing them by withdrawal vertically or by burning.

The upper ends of the side members 23, 115 24, of the stirrup are joined by straps 25, 26, outlining a groove 27 in the bottom of the pool. The contour of the lining upon the bottom of the groove as at 28 between the straps is given by the tool used in the 120

power hammer. When the form is put in place the side of the straps are placed as shown in Fig. 2.

The side fillers 22, 22 take care of the longitudinal expansion but do not relieve from the strain due to transverse expansion of other parts of the form. Across the smaller dimension (generally radial to primary winding) this is small (see Figs. 5 to 8) and I prefer to take care of it wholly by the wax 22' on the outside. For the expansion parallel with the axis of the coil, I prefer to use an internal compressible or removable member in addition to the wax, using metal on opposite sides of the center and some such substance as wax or wood between, which will squeeze out or melt out at a low temperature or which may be burned out, preferably by a blast before heating the secondary, and which is compressible enough to take care (in connection with the wax or separately) of any expansion which takes place before it is removed or destroyed. I have had much success with a construction of the general character of that shown in section in Fig. 6, taken at the same point as 5—5. In this I have used a central portion 29 of easily compressible, expressible or removable material, which need not be a conductor of electricity (I have shown wood in Fig. 6, wax 29' in Fig. 8 and a low fusing alloy 29² in Fig. 9, such as described on page 333 of the 4th edition of *Kent's Handbook*) and have preferred to extend this core throughout the length of the channel. On each side of this compressible or readily removable core I show a strip of conducting metal, 30, 30, which may be a mere strip or of substantial section as desired. Where the narrower dimension is also to be additionally protected a filler of the general character shown at 29³ (Fig. 7) may be used with strips 30', 30'.

After the lining has been rammed about the form, the refractory is dried out, first at atmospheric temperature and afterward in an oven, and the filler pieces are burned out or otherwise removed, giving spaces, seen in Fig. 1, at the sides of the metal stirrup. A very small amount of current is then passed through the transformer primary to induce a slight current in the stirrup as a closed secondary, slightly increasing the heating of the refractory above that received by it in the oven. Either before or after this slight heating of the form (secondary) the intermediate material may be removed or destroyed (as by a flame) or it may be melted out as in the case of wax or a low melting alloy, or it may be squeezed out as in the case of wax. The melting may be done by the heat from the form (secondary). Preferably after the stirrup and lining have been heated in this way molten zinc or a starting charge may be poured in

to occupy the space previously occupied by the fillers and to fill in the channel 27 in the bottom of the pool.

A current may be passed through the transformer sufficiently large for the heat of the induced current in the secondary (stirrup) to sinter the refractory without melting the stirrup. The melting point of the brass being much higher than that of the zinc, (where molten zinc is used) the heat of the stirrup may at the same time be made to maintain the zinc in molten condition and the molten zinc or starting charge yields with the expansion of the stirrup avoiding breakage of the refractory while at the same time heating not only the lower part of the channel where the metal stirrup is of full size but maintaining either the molten zinc, or starting charge, or the material of the stirrup displacing it, in contact with the lining. The drying and sintering may be accomplished by the heating of the form without a molten charge but not quite so advantageously as with the aid of the molten metal.

After the current has been kept on in this manner for a sufficient length of time, where molten zinc has been used or where no molten metal has been poured in, the liquid starting charge is poured in and the furnace is started without the same risk of breaking the stirrup and interrupting the flow of secondary current by reason of the melting of the stirrup before there is a sufficient head of molten metal above it; and without risk of cracking the refractory material by expansion of the form or stirrup. The stirrup finally melts and merges with the starting charge.

Where the starting charge is inserted directly upon the form, without intermediate use of molten zinc, the stirrup should be heated to a higher temperature before the starting charge is poured in than would be required before molten zinc is inserted.

The outside wax and the intermediate material shown between the outer metal strips or bars in Figs. 6—9 take up the transverse expansion of the metal. The wax, (inside or outside) of course, would squeeze out with pressure and melts at a low temperature. It is thus radially displaced by the expanding metal and by the molten zinc or starting charge. Wood compresses slightly, enough to relieve the expansion considerably particularly as the adjoining metal begins to char it before the temperature is very high; but it is best to burn the wood out at the start. The low melting alloys melt at so low a temperature that they may be melted out by the heat from the (secondary) metal strips without subjecting the lining to very serious strain from expansion. In this case, too, the wax cover is highly beneficial.

In order that the current carrying capacity of the upper part of the stirrup may be reduced so as to make this the weakest part electrically and protect against interruption 5 of the secondary circuit at some lower and less accessible point, I make the upper portion of my stirrup hollow, connecting by the straps as described. By this arrangement, too, the molten zinc or molten starting 10 charge fills in the groove across the bottom of the pool between the straps 25 and 26 and protects against interruption of the secondary circuit in case of melting of the straps at the top of the stirrup, automatically 15 "healing" any gap threatened thereby.

It will be evident that my invention is not confined to channels within the space beneath the furnace nor even to those having dominant metal pools but is applicable to 20 all forms wherein a solid form is desired, and where a yielding, destructible or removable filler member can be used to give room for an expansion of the solid form which would otherwise injure or break the furnace. 25 The word filler is used herein to apply to the wax outer covering, the side strips and the intermediate material in the center between outer conducting strips in Figs. 6-9.

It will be evident that, as compared with 30 the filler members or non-metallic part of the section, the metal part of the stirrup is a quasi-permanent part of my form and that the skeleton sides in Figs. 1 and 2 give room for expansion and when expanded, need 35 not completely fill out the spaces within the side channels, *i. e.*, against the outer limiting walls, as the molten zinc, or other molten content used will fill any space left either outside or inside the expanded skeleton side 40 members. The molten zinc or starting charge also fills, to any depth desired, the space in the groove 27 within the bottom of the furnace defined by the spaced top straps or connections, covering the floor of 45 this channeled groove and healing, as above stated, any break in the straps caused by their melting, preventing interruption of the secondary circuit.

It will be evident that the metal strips in 50 Figs. 6-9 are both "outer" strips with respect to the intermediate (middle) section, notwithstanding the wax outside of the strips, and that this arrangement is preferred instead of a metal center and the use 55 of the entire compressible or removable section of the form of outer strips in order to bring the metal strips into more intimate engagement with the channel walls, reducing the extent of engaging surfaces of the wood 60 or low-fusing metal, for example. Where the outer coating of wax is not very thick, as in my preferred use, heating of the metal soon brings the latter into substantial contact with the channel wall.

It will be evident that the manner of supporting the fillers upon the skeleton sides during the placing of the lining as well as the determination of the material to be used for the fillers and whether these shall be removed by destroying them in position or 65 by withdrawing them or by squeezing them out or melting them out will depend upon the judgment of the operator, the shape of the stirrup, the accessibility of the channel parts from within the furnace and other 70 factors which vary with the installation and the conditions under which it is placed.

It will also be evident that the temporary filler may be located either outside the main form or between parts thereof, and may act 80 by virtue of its compressibility, its mobility under pressure, its fluidity when heated, its destructibility or its removability.

What I claim as new and desire to secure by Letters Patent is:—

1. A form for outlining the channel path in an electric furnace having a cross section of different materials, one a conductor of electricity and the other adapted to occupy space during the placing of the lining and 90 to permit expansion of the conducting material into this space subsequently.

2. A form for outlining the channel path in an electric furnace having a cross section of differing materials having different heat-resisting capacities and one of them a conductor of electricity.

3. A form for outlining the channel path in an electric furnace comprising an inner conductor of electricity and an outer temporary coating of yieldable material adapted to permit expansion of the conductor.

4. A form for outlining the channel path in an electric furnace, comprising an inner conductor of electricity and an outer covering therefor adapted to be melted or destroyed at a temperature lower than the melting point of the conductor.

5. A form for outlining the channel path in an electric furnace having, in cross section, conducting material on the opposite sides and material of lower conductivity in between.

6. A form for outlining the channel path in an electric furnace having, in cross section, electrically conducting material on opposite sides of the center and an intermediate temporary filler therebetween.

7. A form for outlining the channel path in an electric furnace having, in cross section, electrically conducting material on opposite sides of the center and temporary filling material between them and also outside of the electrically conducting material.

8. A form for outlining the channel path in an electric furnace having a non-homogeneous cross section and of material and shape adapting to destruction of the form

- as a preliminary to the substitution of the furnace metal.
9. A form for outlining the channel path in an electric furnace having a longitudinally extending electrically conducting material and an outside wax covering.
10. A form for outlining the channel path in an electric furnace having in cross section an electrical conductor and a low melting point core therefor.
11. A form for outlining the channel path in an electric furnace, of wood having a hollow center and closed at the bottom.
12. A form for outlining the channel path in an electric furnace having a portion of its cross section of high heat-resisting quality and a portion having cushioning functions or removable therefrom.
13. A form for outlining the channel path in an electric furnace which in cross section has material on opposite sides of the center which does not extend to the center and suited thereby for destruction of the form to give place to the furnace metal.
14. A form for outlining the channel path in an electric furnace containing a low-melting-point alloy.
15. A form for outlining the channel path in an electric furnace comprising a stirrup and filler material therefor removable to allow expansion room for the stirrup.
16. A form for outlining the channel path in an electric furnace having removable filler members located in the position of longitudinal expansion of the form.
17. A form for outlining the channel path in an electric furnace comprising a lower electrically conducting channel member and an upper electrically conducting skeleton connecting therewith to complete a secondary circuit in combination with temporary filling for the sides of the skeleton.
18. A form for outlining the channel path in an electric furnace comprising a lower metallic member, sides connected therewith and spaced top metallic connections between the upper ends of the sides.
19. A form for outlining the channel path in an electric furnace comprising a lower member of full cross section, sides connected therewith and spaced metallic connections between the sides at the top.
20. A form for outlining the channel path in an electric furnace comprising a lower V-shaped metallic member, substantially parallel metallic skeleton sides and metallic connection at the top between the sides.
21. A form for outlining the channel path in an electric furnace of electrically conducting material and having its cross section of smallest area at the top to provide for interruption first at that point.
22. A form for outlining the channel path in an electric furnace of smaller size in cross section than the cross section of the channel in combination with molten metal filling the space between the form and the inner channel walls.
23. A form for outlining the channel path in an electric furnace having a metallic member and also a more temporary non-metallic member, each extending longitudinally throughout the length of the channel.
24. The method of forming an electric furnace channel which consists in providing an electric conductor extending the length of the channel and of less cross section than the channel at the sides in the direction of the longitudinal expansion of the channel, completing the cross section of the conductor for the initial formation of the channel, removing the additional material added, heating the conductor to dry out the channel and finally melting out the conductor.
25. The process of forming an electric furnace channel and protecting its sides from injury by expansion of the form which consists in constructing a part of the cross section of the form of yieldable, removable or destructible material to relieve from expansive strain and taking advantage of this capacity to permit drying out of the channel walls by heating the form.
26. The process of forming an electric furnace channel lining which consists in providing a metallic member extending the length of the channel having a part only of the cross section of the channel where it is desired to relieve the channel wall from strains due to expansion, providing a temporary filler to complete the form there to full channel cross section, forming the channel wall about the member and filler removing the temporary filler to permit expansion into the space occupied by it previously and heating the metallic member to dry and sinter the lining at the same time that molten metal is supplied in conjunction with the metal member.
27. The process of forming a channel lining which consists in providing a metallic member of full channel size throughout a portion of the contour to be formed, providing temporary fillers to complete the form to full channel size throughout another portion thereof, placing the channel wall about the form, removing the temporary fillers to permit expansion, heating the metallic form to dry and sinter the lining at the same time that molten metal is supplied to fill the space between the second portion of the channel and the channel walls, and ultimately melting out the metallic form.
28. The process of forming and drying the channel of an electric furnace which consists in forming a channel portion of full

- channel size adapted to expand, connecting the ends of this channel portion by a metallic skeleton smaller than the channel section where expansion would take place, 5 closing the top to form a closed metallic circuit, using removable fillers to complete the channel size in the skeleton portion, placing the channel wall about the form, removing the fillers and passing induced electric current through the secondary path formed after removal of the fillers to dry and sinter the lining and ultimately melt the same.
29. The process of drying a lining and starting an electric furnace which consists in using a metallic form for the furnace channel throughout the length of the channel and skeletonized to permit expansion throughout a portion at least of its length, with a removable filler for temporarily increasing the form to channel size in the skeleton portion, placing a lining about the form and filler, baking the lining and further drying the lining by induced current through the form after removal of the filler, 25 and in the presence of a molten charge of lower melting point than the metallic form, to sinter the adjoining lining and maintain the charge molten.
30. The process of drying a lining and starting an electric furnace which consists in using a metallic form for the furnace channel throughout the length of the channel but not of the full channel cross section with a removable filler for temporarily increasing the form to channel size, placing a lining about the form and filler, baking the lining, further drying the lining by induced current through the form before or after removal of the filler, applying a molten charge to sinter the adjoining lining and maintain the charge molten and ultimately increasing the induced current to melt out the metal form.
31. The process of drying a lining and starting an electric furnace which consists in using a metallic form for the furnace channel throughout the length of the channel skeletonized to permit expansion throughout a portion at least of its length, with a removable filler for temporarily increasing the form to channel size in the skeleton portion, placing a lining about the form and filler, baking the lining, further drying the lining by induced current through the form after removal of the filler and in the presence of a molten charge to sinter the adjoining lining and ultimately increasing the induced current to melt out the metal form while the form is subjected to a substantial hydraulic 60 head of molten metal.
32. The process of forming a channel lining for an electric furnace and starting the furnace which consists in providing a closed circuit metallic channel form, throughout the length of the channel and reduced in

section at the sides to provide for expansion, filling out by removable material to the size of the channel at the reduced portion of the form, placing a lining about the form, removing the removable portion of the composite form, partially drying the refractory lining, passing electric current through the form to sinter the refractory lining, providing a head of molten metal over and in fluid communication with the form and increasing the current through the form to melt it.

33. The method of starting an electric furnace of channel type which consists in providing a metal form within the channel having a part of less cross section than the channel, leaving expansion room, placing a lining about the form, filling in about said part with molten metal and passing electric current through the form to melt the form 80 and start the furnace.

34. The method of starting an electric furnace of channel type which consists in providing a metal form within the channel having a part of less cross section than the channel, leaving expansion room, placing a lining about the form, filling in about said part with molten metal having a lower melting point than the metal of the form and passing electric current through the form 85 to sinter the lining and maintain the metal of lower melting point in molten condition.

35. The method of starting an electric furnace of channel type which consists in providing a metal form within the channel having a part of less cross section than the channel, leaving expansion room, placing a lining about the form, filling in about said part with molten metal having a lower melting point than the metal of the form, passing electric current through the form to sinter the lining and maintain the metal of lower melting point in molten condition, providing a fluid head of molten metal above 100 the form and in fluid communication therewith and increasing the current through the form to melt the form.

36. The process of starting an electric furnace of channel type which consists in providing a metal form within the channel, placing a lining about the form, pouring in communication therewith molten metal having a melting point below that of the metal form, heating the form by electric current to raise 115 its temperature below its melting point but above that of the molten metal, supplying a head of molten metal of a higher melting point than the first molten metal and increasing the electric flow through the form 120 to melt it while subjecting it to the pressure due to said head.

37. The method of starting an electric furnace of channel type which consists in providing a metal form for the channel, 130

placing a lining about the form, applying pressure to the form by a head of molten metal in communication therewith and melting the form by electric current while it is subject to the head of molten metal.

38. The method of starting an electric furnace of channel type which consists in providing a metal form within the channel, placing a lining about the form, heating the metal form by passing an electric cur-

rent through it, applying pressure to said form by a head of molten material and increasing the flow of electric current through the form to melt it while it is subject to the head of molten metal.
